BRICK PRESS BATCH DISTRIBUTOR

Fred O. Schob, Pittsburgh, Pa., assignor to Harbison-Walker Refractories Company, Pittsburgh, Pa., a corporation of Pennsylvania

Application April 7, 1955, Serial No. 499,787

3 Claims. (Cl. 25—103)

This invention relates to brick presses for manufacturing refractory bricks, and more particularly to the feeding of batch material to the presses.

The well-known Boyd toggle press is an example of the kind of press to which this invention applies, but the invention is not limited thereto but is applicable also to other presses which form bricks from a granular batch. Many of the important properties of bricks made in such presses are governed by their bulk density, the control of which will depend on the success in feeding the same weight of uniformly mixed material to each mold box at each pressing. Refractory bricks are made of refractory grains of graded sizes, together with water for tempering or lubrication. No other bond may be needed in order to give the bricks enough strength to be handled through drying and firing. In other cases, such bonds as starch, lime or sulphite waste liquor may be used. In any case, however, the batch is difficult to handle in ordinary equipment, because it is moist enough to be resistant to easy flowing.

Present brick press charging devices require the semi-dry granular batch to flow laterally from the feed pipes into the charging box, because the pipes have to be placed near the opposite sides of the charger due to the central location of the pitman arm that operates the toggle. During this lateral flow of the batch, segregation of the various particles occurs and causes trouble. Thus, frequently the largest particles flow forward into the front end of the charging box so that the finished brick will be different in composition or structure from one end to the other. Such brick often have to be scrapped. Furthermore, this dependence on material flow by gravity often results in bricks which are poorly filled out. In a multiple mold set up, the several bricks may have different weights, due to unequal charging. The lighter bricks will be unsatisfactory because high density is almost universally sought for in such products. Moreover, in refractory batches of certain types; for example, a fire clay batch made of flint clay and plastic clay, the rolling of particles leads to an unwanted segregation. The plastic clay fines tend to roll up into small balls that are objectionable in the product and that prevent uniform distribution of the plastic clay which is relied upon for developing strong bonding.

In an attempt to correct this situation, attempts have been made to agitate or mix up the segregated batch after it enters the charger. These attempts have not been successful, however, because the mixing devices have merely churned around in the batch and cut paths through it without redistributing the fine and coarse particles throughout the charger to produce a uniform mix.

It is among the objects of this invention to provide brick press feeding apparatus which prevents objectionable segregation of the batch from occurring in the first place, and which will not pack the batch into a hard mass in distributing the batch evenly throughout the charger.

In accordance with this invention, a charging box having an open top and bottom is movable forward from a batch-receiving position to a discharging position over

2

the molding cavity of a brick press. A feed hopper empties into the box when it is in its rear position, and a distributing housing on the hopper has an open bottom that empties into the hopper. The top of this housing has an inlet opening near one side, to which an upright conduit is connected for delivering batch material to the housing. Journaled in the housing is a central vertical shaft, from which a distributing arm extends laterally. This arm, preferably, includes vertical fingers spaced lengthwise of it, and the shaft is rotated to sweep the arm in a circular path around the inside of the housing in order to remove batch material from beneath the inlet opening as it enters the housing and to distribute it throughout the housing. It is highly desirable that the shaft-rotating means be formed to stall when the resistance encountered by the arm exceeds a predetermined value. This will prevent the arm from packing the batch in the housing.

The preferred embodiment of the invention is illustrated 20 in the accompanying drawings, in which

Fig. 1 is a fragmentary vertical section through the upper part of a brick press;

Fig. 2 is an enlarged plan view of my feeding apparatus alone; and

Fig. 3 is a view of the rear end of the feeding apparatus. Referring to Fig. 1 of the drawings, a brick press frame 1 is provided near its front with a molding cavity 2 in which bricks 3 are pressed between upper and lower dies 4 and 5. The upper die is reciprocated vertically by a 30 cross head 7 slidably mounted in guides 8 at opposite sides of the frame. The cross head is moved up and down by toggle links 9 and 10 pivotally connected to the front end of a pitman arm 12 that extends back through the center of the machine to a crank pin 13 carried by a large gear 14. Synchronized with the movements of the dies is a charger 35 that is slidably mounted on a table 16 directly behind the mold cavity. The front half of the charger is in the form of a box 17 that has an open top and bottom. The rear half of the charger includes a horizontal plate 18 on 40 a level with the top of the box. Pivotally mounted beneath this plate is the front end of a rod 19 which extends back into an arm 20 that is swung back and forth in a well-known manner to reciprocate the charger over the table. The charging box receives a charge brickmaking material or batch in its rear position, and then is moved forward when the upper die is raised. In its forward position the box registers with the mold cavity and the material in the charger drops into the cavity. When a plurality of bricks are being made at the same time, the 45 charging box and molding cavity are provided with partitions, as is well-known.

It is a feature of this invention that every time the charging box is retracted it is filled with a uniform mixture of granular material, in which there is no objectionable segregation of coarse and fine particles. Accordingly, a short 50 hopper 22 is rigidly mounted in the frame in any suitable manner in a location directly above the charging box 17 when the latter is in its rear or retracted position. The hopper has an open bottom the same size as the top of the box and engages it lightly, but the bottom of the hopper is closed by the charger plate 18 when the charger is moved forward. The hopper supports a distributing housing 23 that has an opening in its bottom of about the same size as the open top of the hopper. The housing has an 55 arcuate portion that projects behind the hopper for a purpose that will soon become clear.

In order to deliver the semi-dry batch of brick-making material to this feeding apparatus, the conduit 25 through which the material is fed by gravity has to be located at one side of pitman arm 12. The conduit should be as straight and vertical as possible. Accordingly, as shown in Fig. 2, the top of distributing housing 23 is provided

near one side with an inlet opening 26 communicating with the lower end of the conduit. Mounted on the housing beside the conduit and beneath the pitman arm is a motor 27 that drives a short vertical shaft 28 projecting down into the center of the housing. The lower end of this shaft supports a plurality of radial arms, each of which is long enough to extend across inlet opening 26. The purpose of these arms is to sweep or carry the incoming material around to the other parts of the housing in order to distribute the batch uniformly therein. This distribution occurs as the material enters the housing from the conduit and before any segregation of coarse and fine particles can take place.

Each distributing arm, preferably, is formed from a horizontal bar 30 located near the top of the housing and having several fingers 31 extending downward from it. These fingers act similarly to the tines of a rake and thus rake the batch around in the housing. They are long enough to nearly touch the bottom of the projecting arcuate portion of the housing. The fingers are spaced apart to keep the material from packing between them, but most suitably they are disposed at an oblique angle to the longitudinal axes of the bars in order to exert more of a pushing action against the batch. Some of the fingers are reversed relative to others to help keep the batch from packing at the center of the housing.

The motor rotates the distributing arms as long as the batch in the housing is fairly loose, but the motor is designed to stall or stop as soon as the housing becomes so full that the material will begin to pack. A desirable type of motor for this purpose is a pneumatic motor, to which air is delivered at a predetermined pressure through a pressure regulator 33 and hose 34 as shown in Fig. 3. As soon as the force exerted against the arms by the resistance of the material in the housing equals the air pressure that operates the motor, the motor will stop without being damaged. Consequently, the batch will not be packed into a solid mass in the housing, but will remain relatively loose.

Assuming that the feed conduit, distributing housing, hopper and charging box are all full of the desired batch, the charger is moved forward to fill the mold cavity and then is retracted. As soon as the empty charging box is pulled back beneath the hopper, the batch in the hopper fills the box, the material in the housing falls straight down into the hopper, the motor starts to rotate the distributor arms, and the material in the feed conduit starts to move down into the distributing housing. As fast as the material enters the housing, the distributing arms carry it around and distribute it uniformly throughout the housing before segregation can occur. As the housing becomes filled in this manner, resistance to rotation of the arms will increase until they and the motor stall. The arms will then remain motionless until the charging box is moved forward and emptied and returned for a new charge.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. Feeding apparatus for use with a brick press provided with a molding cavity, the feeding apparatus comprising a horizontally reciprocable charging box having an open top and bottom and movable forward from a batch-receiving position to a discharging position over said cavity, a hopper emptying into the box in its rear position,

a distributing housing on the hopper having an open bottom emptying into the hopper, the top of the housing having an inlet opening near one side, an upright conduit connected with said opening for delivering batch material to the housing, a central vertical shaft journaled in the housing, a distributor arm extending laterally away from the shaft, and means for rotating the shaft to sweep the arm in a circular horizontal path around the inside of the housing to remove batch material from beneath said inlet opening and distribute it throughout the housing, said shaft-rotating means includes a pneumatic motor and an air pressure reducer connected with the inlet of the motor, whereby the motor will stall whenever the resistance to movement of said arm equals the air pressure delivered to the motor by said reducer.

2. Feeding apparatus for use with a brick press provided with a molding cavity, the feeding apparatus comprising a horizontally reciprocable charging box having an open top and bottom and movable forward from a batch-receiving position to a discharging position over said cavity, a hopper emptying into the box in its rear position, a distributing housing on the hopper having an open bottom emptying into the hopper, the top of the housing having an inlet opening near one side, an upright conduit connected with said opening for delivering batch material to the housing, a central vertical shaft journaled in the housing, a distributor arm extending laterally away from the shaft, a motor for rotating the shaft to sweep the arm in a circular horizontal path around the inside of the housing to remove batch material from beneath said inlet opening and distribute it throughout the housing, and means for operating the motor with a predetermined torque, whereby the motor will be stalled when the resistance encountered by said arm exceeds said torque.

3. Feeding apparatus for use with a brick press provided with a molding cavity, the feeding apparatus comprising a horizontally reciprocable charging box having an open top and bottom and movable forward from a batch-receiving position to a discharging position over said cavity, a hopper emptying into the box in its rear position, the side walls of the hopper being substantially vertical, a distributing housing on the hopper having an open bottom substantially the same size as the opening in top of the hopper and emptying into the hopper, the top of the housing having an inlet opening near one side directly above the hopper, an upright conduit connected with said opening for delivering batch material to the housing, a central vertical shaft journaled in the housing, a distributor arm extending laterally away from the shaft, and means for rotating the shaft to sweep the arm in a circular horizontal path around the inside of the housing to remove batch material from beneath said inlet opening and distribute it throughout the housing on top of the batch material in the underlying hopper.
